UNITED STATES PATENT OFFICE.

FREDERICK C. SPENCER, OF GUILFORD, CONNECTICUT.

LIFTING-JACK.

1,148,868.

Specification of Letters Patent Patented Aug. 3, 1915.

Application filed September 19, 1913. Serial No. 790,690.

To all whom it may concern:

Be it known that I, FREDERICK C. SPENCER, a citizen of the United States, and resident of Guilford, in the county of New Haven and State of Connecticut, have invented a new and useful Improvement in Lifting-Jacks, of which the following is a specification.

My invention relates to a lifting jack with the object in view of providing a simple, light, efficient and inexpensive jack for use in connection with automobiles in particular, and vehicles in general.

A practical embodiment of the invention is represented in the accompanying drawings in which,

Figure 1 is a view of the jack in side elevation, the lifting screw being partially elevated. Fig. 2 is a vertical section of the same. Fig. 3 is a transverse section in the plane of the line A—A of Fig. 1, and Fig. 4 is a transverse section in the plane of the line B—B of Fig. 1.

The pedestal of the jack is denoted by 1, and is made conveniently in the form of a tubular casting with its base portion laterally extended and provided with fillets or webs 2 connecting it with the body portion to strengthen it. This pedestal is provided at its upper end with an annular seat 3 for a pawl carrying ring 4 and with an annular groove 5 in that portion surrounded by the pawl ring 4, for the reception of a screw 6 to prevent the unintentional displacement of the ring 4. The said pedestal is further provided on its interior with vertical grooves 7 and 8, see Fig. 4, for the reception of a cross pin 9, in the lower end of the lifting screw 10, to prevent the screw 10 from turning. The lifting screw 10 is intended to extend within the tubular pedestal 1, freely and is provided at its upper end with a cap 11 swiveled on the end of the screw so that when the cap 11 is pressed against the object to be raised, the screw may turn freely within the cap as is usual. On the body of the screw 10, there is located a nut 12, the periphery of which is provided with teeth 13, forming of the nut 12 what I am pleased to call a pinion nut.

The pawl carrying ring 4 hereinafter referred to has an extension 14, recessed at 15, to receive therein a double-acting pawl 16, pivotally secured in position by a pin 17, extending, in the present instance, through the opposite walls of the recess 15.

To hold the pawl 16 in either of its two opposite tilted positions, a plunger 18 is located in a socket 19, in the extension 14, and is pressed toward the pawl by means of a spring 20 seated in the socket 19, back of the plunger 18. The extension 14 is further provided with a pair of depending ears 21, 22, between which the inner end of an operating lever 23 is pivoted by means of a pin 24. When out of use, the lever 23 may be swung down into the position shown in full lines in Figs. 1 and 2, and when in use, the lever 23 is raised into the position shown in dotted lines in Fig. 1.

The nut 12 rests on the top of the pedestal 1, and transmits the weight of the screw 10 and whatever is supported on the screw 10, to the top of the pedestal 1.

In operation, the screw 10 may first be adjusted to such a height as to bring the cap 11 into contact with the part to be raised, by simply lifting the screw 10 and nut 12 upwardly out of engagement with the pawl 16, and then hauling the nut 12 up or down on the screw 10, so that when the screw is allowed to drop into the pedestal and the nut 12 seated on top of the pedestal, the swivel cap 11 will be at the proper height. The nut is then operated to lift the screw by raising the lever 23 into the position shown in dotted lines Fig. 1, and turning the nut 12 to the right, the pawl 16 being engaged with the pinion nut as shown in dotted lines Fig. 3. As the lever 23 is moved backward to take a hold on the pinion nut 12, the pawl rides over one or more of the teeth 13, depending upon how far the lever is swung backward. The lever is then pulled forward, the pawl engaging the pinion nut and causing the latter to again turn. These operations are repeated until the screw has reached the proper height. When it is desired to lower the screw, the pawl 16 is tilted into the position shown in full lines in Fig. 3, and the lever 23 is again worked back and forth, in this instance taking effect on its backward stroke to turn the nut 12 to the left and thereby lowering the screw and whatever is supported thereon.

It will be observed that the pedestal may be cast complete without requiring any tool work, that the pawl carrying ring may also be cast complete without requiring any tool work, and that the pinion nut may be cast requiring only the screw-threads to be tooled, and this, together with the threads

on the lifting screw, are the only parts that require tooling.

It will further be observed that the screw, when the parts are assembled, is locked in position within the pedestal, the pin 9 being inserted in place by allowing the screw 10 to project through the bottom of the tubular base or pedestal to receive the pin 9, and then lifted into position to receive the swivel cap 11 which may be secured in position on the reduced end of the screw 10 by upsetting the end 25 of the screw. An interior shoulder 26 near the upper end of the pedestal 1, limits the upward movement of the screw 10, by the engagement of the pin 9 with the shoulder. This enables the jack to be made in a very inexpensive manner, and furthermore, the employment of a single pinion nut, and this in axial alignment with the pedestal and lifting screw permits the folding of the jack when not in use into a very compact form for transportation.

What I claim is:

1. A lifting jack comprising a tubular pedestal, a lifting screw free to move up and down within the pedestal, means for holding the screw against rotation within the pedestal, a pinion nut engaged with the

lifting screw and bearing on top of the pedestal and free to be lifted bodily with the screw, a pawl carrying ring mounted on the pedestal below the said pinion nut, a double acting pawl carried by the ring and a ring and pawl operating lever pivoted to the ring below the pawl.

2. A lifting jack comprising a tubular pedestal, a lifting screw adapted to move up and down within the pedestal, means for preventing the screw from rotating within the pedestal, a pinion nut engaged with the screw and bearing on the pedestal, a pawl carrying ring free to rotate on the pedestal below said pinion nut, the pedestal and the ring being provided, the one with a groove and the other with a projection adapted to enter the groove to lock the ring against vertical displacement on the pedestal and a ring and pawl operating lever pivoted to the ring below the pawl.

In testimony, that I claim the foregoing as my invention, I have signed my name in presence of two witnesses, this 17th day of September, 1913.

FREDERICK C. SPENCER.
